(57) **CLAIM**

The ornamental design for a clamp for flexible medical lines, as shown.

DESCRIPTION

FIG. 1 is a perspective view of the top, one side and one end of a clamp for flexible medical lines in the open condition showing my new design;

FIG. 2 is a perspective view of the bottom, said one side and said one end thereof;

FIG. 3 is a side elevational view of said one side thereof;

FIG. 4 is a side elevational view of said opposite side thereof;

FIG. 5 is an end elevational view of the opposite end thereof;

FIG. 6 is an end elevational view of said one end thereof;

FIG. 7 is a top plan view thereof;

FIG. 8 is a bottom plan view thereof;

FIG. 9 is a perspective view of the top, one side and one end of the clamp in the closed condition;

FIG. 10 is a perspective view of the bottom, the opposite side and said one end thereof;

FIG. 11 is a side elevational view of the opposite thereof;

FIG. 12 is a side elevational view of said one side thereof;

FIG. 13 is an end view of said one end thereof;

FIG. 14 is an end elevational view of the opposite end thereof;

FIG. 15 is a top plan view thereof; and,

FIG. 16 is a bottom plan view thereof.
